UNITED STATES PATENT OFFICE

WILLIAM A. GEIGER, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed February 13, 1928. Serial No. 254,010.

This invention relates to improvements in railway draft riggings.

As is well known to those skilled in the art, there are in service today on the railways, a great number of the old style couplers having shouldered butts or butts having liner blocks, which style of couplers was originally intended for use with riveted yoke straps. There is a constant tendency to employ with such couplers, hooded cast yokes in lieu of the yoke straps and this necessitates the use of some form of locking blocks or keys to provide an operative draft connection between the liner block type of coupler and hooded yoke.

It is also well known that there has heretofore been a constant source of trouble in maintaining the couplers properly aligned with the shock absorbing device, this being true not only of the old style couplers but likewise true of the more modern coupler in which the shank is not provided with liner blocks or shoulders. The inability to maintain proper alignment of the couplers arises from several causes, among them being the looseness of the connection with the yoke and the wearing or distortion of the customary carry iron which permits the head end of the coupler to droop or sag and, on account of the loose connection with the yoke element, the coupler is permitted to tilt or cock upwardly during the coupling of two cars. This drooping and tilting of the coupler not only accentuates the wear and distortion of the carry iron but also causes destruction of the end buffer casting and further allows of the application of eccentric blows to the shock absorbing device, which is undesirable and frequently destructive.

One object of my invention is to provide a draft rigging wherein simple and relatively inexpensive means are provided for maintaining a coupler of the shouldered or liner block type in its proper horizontal position in alignment with the shock absorbing device whereby to prevent the wear or distortion of the parts and eliminate the application of eccentric blows to the shock absorbing device.

A more specific object of my invention is to provide an improved yoke to which may be

interlocked a coupler of the shouldered or liner block type and which yoke is provided with means for maintaining the horizontal position of the coupler in all operative positions of the parts and more especially such an arrangement wherein a longer stroke of the draft gear is permitted than has heretofore been customary in standard types of draft gears.

A still further object of my invention is to provide a novel yoke having the characteristics above indicated, which yoke is provided with integral means for limiting the draft movement of the yoke and preferably such means so arranged as to limit the draft action to an amount less than the permissible buff action.

Other objects of the invention will more clearly appear from the description and claims hereinafter following.

In the drawing forming a part of this specification, Fig. 1 is a longitudinal, vertical, sectional view of a portion of a railway car showing my improvements in connection therewith. Fig. 2 is a horizontal, longitudinal, sectional view corresponding to the line 2—2 of Fig. 1. Fig. 3 is a vertical, transverse, sectional view corresponding to the line 3—3 of Fig. 1. And Fig. 4 is a broken view similar to Fig. 1, illustrating another embodiment of my invention.

Referring first to the construction illustrated in Figs. 1, 2 and 3, 10—10 denote the usual channel draft sills of a railway car underframe and which may constitute parts of the usual center sills. The usual bolster is indicated at 11, the same having a center filler casting 12 which, in the construction shown, is provided with forward extensions 13—13 having vertical flanges 14 at their front ends, said flanges 14 constituting the rear vertical stops of the draft rigging. The ends of the draft sills are suitably connected to the end sill 15 of the car and the opening provided for the reception of the coupler is reinforced by a suitable casting 16 which also constitutes the usual buffer block of the car. The coupler is sustained by the usual carry iron 17 and the parts of the draft rigging are sustained by detachable saddle

plates 18—18 bolted to the lower flanges of the draft sills.

In carrying out my invention, I employ a novel yoke designated generally by the reference A; locking blocks B—B, the latter co-acting with a coupler C of the older liner block type. Within the yoke I have indicated conventionally a friction shock absorbing device D which may be of any suitable or desired construction, the one shown having a plurality of friction elements including a pressure transmitting wedge 19 at its front end and arranged for a long compression stroke, preferably 5" or 6".

The coupler C is provided with the usual horn 20, shank 21 and upper and lower liner blocks 22—22 at the butt end thereof. The coupler shown is one of well known type, as will be apparent to those skilled in the art. The butt of said coupler normally engages a front follower E which is or may be of the usual rectangular form.

The yoke A is shown in the form of a casting and comprises upper and lower arms 23—23 united at their rear ends by a vertical section 24. At its front end, the yoke A is formed with a tubular or box-like section integral with the arms 23, said section comprising upper and lower walls 25—26 and side walls 27—27.

The top wall 25 extends horizontally for the greater portion of its length as indicated at 125 and, at its outer end, has an upstanding flange 225 normally engaging the horn 20. Rearwardly of the horizontal section 125, said top wall is upwardly offset as indicated at 325, so as to bring it into alignment with the upper arms 23 of the yoke. The lower wall 26 extends horizontally from its outer end to a point adjacent the shoulders or liner blocks of the coupler where it is downwardly offset as indicated at 126, the two offsets thus providing rearwardly facing shoulders 425 and 426. As will be understood, the distance between the top and bottom walls 25 and 26 is just sufficient to permit the insertion of the enlarged butt end of the coupler.

To sustain the head end of the coupler after the liner blocks are in position, I may employ an insert 40 at the outer end of the lower wall thereof, said insert being maintained in place by any suitable means such as a dowel pin 41, engaged in corresponding openings in said bottom wall 26. Said insert 40 will be put in place after the enlarged butt has been moved to its rearmost position but before the locking blocks B are inserted, it being evident that there will be sufficient clearance to permit elevation of the coupler shank for this purpose.

The side walls 27 of the yoke A are forwardly laterally flared, as best indicated in Fig. 2. In line with the shoulders of the coupler, the side walls are provided with

aligned openings 127—127 near the top and bottom of the yoke, said slots being of angular formation and conforming to the angular cross section of the locking keys or blocks B which are inserted laterally so that the inturned flanges or shoulders 28 thereof will be positioned between the yoke shoulders 425 and 426, and the shoulders provided by the liner blocks 22. In this way, it will be observed that the coupler and yoke necessarily move in unison in a draft action, thus actuating the yoke when the coupler is pulled outwardly.

The front follower E normally engages front vertical stop lugs 29—29 formed on lug castings, and it will also be noted that said lug castings have narrow vertically disposed flanges 30—30 on their inner sides, which partially or wholly overlie the ends of the locking blocks B when the yoke and coupler are in position. In this manner, the locking blocks are confined against lateral shifting and thus maintained in operative position and danger of fouling of the ends of said locking blocks with any other projecting part of the stop lugs is thereby avoided.

Each of the upper and lower arms 23 of the yoke A is provided with lateral projections 123—123, as best shown in Fig. 2, said projections having forwardly facing shoulders 223 which are normally disposed at a distance from the front stop lugs 29 corresponding to the desired draft action. Said shoulders 223 are in line with the front stop lugs 29 and consequently, in a draft action, said shoulders 223 will engage the stop shoulders 29 and limit the draft movement of the yoke and consequently the draft action of the shock absorbing device to the desired amount, which, preferably, will not exceed the customary stroke of $2\frac{3}{4}$ " now employed.

In a buff action, it is evident that the yoke A and coupler and front follower E will move rearwardly in unison and the full long compression stroke of the shock absorbing device D will be obtained. The limit of the buff action is determined by the follower E engaging the outer end of the shell element of the friction device. The space between the flange 225 and the end buffer casting will preferably be made slightly greater than the normal buff travel but any overload or excessive buff movement will be further resisted by the engagement of said yoke flange 225 with the buffer casting, as will be obvious.

Referring to the modification shown in Fig. 4, the only changes involved are with respect to the yoke F and the coupler G. The latter is of an older type but somewhat different from the coupler C in that the coupler G has a much deeper butt 42 so that the support at the bottom of the butt will necessarily be in a lower plane than the support

for the butt of the coupler C. In the Fig. 4 modification, the upper wall of the yoke F extends horizontally throughout its entire length, as indicated at 43, and the same will be provided with an interior vertical shoulder or lug 44 adapted to directly engage the upper shoulder 45 of the coupler butt. With this arrangement only one locking key 46 is necessary, the same being entered laterally through the side walls of the yoke F and resting upon the bottom wall 47 of the front end of the yoke, as clearly shown in the figure. A support insert 48 is employed in this construction, to sustain the outer or head end of the coupler, said insert 48 being of considerably deeper dimension, however, due to the fact that the bottom wall 47 of the yoke is necessarily in a lower plane than the bottom wall of the yoke A. The operation and functions of the parts are the same as those above set forth in connection with the structure shown in Figs. 1, 2 and 3.

With the arrangement of yoke and connections for the liner block types of coupler shown, it will be observed that the center line of the coupler will always be maintained in alignment with the center line or axis of the shock absorbing device, there being no possibility of the coupler tilting with respect to the yoke. Furthermore, due to the fact that the bottom walls of the yoke are extended outwardly beyond the carry iron and to points in line with the coupler head, drooping or sagging of the free end of the coupler is eliminated and hence excessive wear or distortion of the carry iron or application of eccentric blows is prevented.

Although I have herein shown and described what I now consider the preferred manner of carrying out my invention, the same is merely illustrative and I contemplate all changes and modifications that come within the scope of the claims appended hereto.

I claim:

1. As an article of manufacture, a combined alining and draft member for draft riggings comprising: A loop portion adapted to receive a cushioning device therein; a hollow hood portion at one end of said loop portion adapted to receive the shank of a coupler having an enlarged, shouldered butt with liner blocks thereon, said hood being shouldered to co-operate with said liner blocks, said shoulders of the hood being of such a size as to freely receive the shouldered coupler butt therebetween; a bottom wall extended forwardly from said hood portion to a point approximately in line with the coupler head; and detachable means, at the outer end of said wall for supporting the shank of the coupler to maintain the axis of the coupler constant with reference to the center line of said draft member, said detachable means when removed permitting insertion of

the coupler shank through the outer end of the hood.

2. In a draft rigging, the combination with draft sills; of front and rear stop means; a shock absorbing device of relatively long compression stroke; a yoke; and means limiting the draft movement of said yoke to less than the compression stroke of said device, said means including portions formed integrally with said yoke and engaging the front stop means of the sills.

3. In a railway draft rigging, the combination with spaced draft sills; of front and rear stops on said sills; a coupler; a yoke connected to the coupler; a front main follower and a shock absorbing mechanism within the yoke, said shock absorbing mechanism including a friction shell having the front end thereof spaced from said front follower, engagement of said front follower and shell limiting the compression stroke of the mechanism in buff; stop flanges on the yoke normally disposed inwardly of said front stops and spaced a distance therefrom less than the normal spacing between the front follower and front end of the friction shell, thereby restricting the draft stroke of the shock absorbing mechanism to less than the buffing stroke thereof.

In witness that I claim the foregoing I have hereunto subscribed my name this 6th day of Febr., 1928.

WILLIAM A. GEIGER.
